UNITED STATES PATENT OFFICE.

MAX A. SKALL, OF NEW YORK, N. Y.

DESIGN FOR AN ATTACHMENT FOR DISPLAY-CASES.

40,419.

Specification for Design.

Patented Dec. 28, 1909.

Application filed August 13, 1909. Serial No. 512,761. Term of patent 7 years.

To all whom it may concern:

Be it known that I, MAX A. SKALL, a citizen of the United States of America, residing at New York, in the borough of the Bronx, county and State of New York, have invented a new, original, and ornamental Design for an Attachment for Display-Cases, of which the following is a specification, reference being had to the accompanying drawing, forming a part thereof.

I claim:

The ornamental design for an attachment for display-cases, as shown.

MAX A. SKALL.
